BICYCLOAZAOCTANE DERIVATIVES

Leonard M. Rice, Baltimore, Md., and Charles H. Grogan, Falls Church, Va., assignors to The Geschickter Fund for Medical Research, Inc., Washington, D. C., a corporation of New York

No Drawing. Application January 4, 1955,
Serial No. 479,872

9 Claims. (Cl. 260—239)

This invention relates to compositions of matter, particularly to chemo-therapeutic organic compounds and methods of their preparation, and more particularly to compounds of value in the treatment of cardio-vascular and other diseases.

Specifically the invention relates to bicycloazaoctane and the simple salts and the mono- and bis-quaternary salts of bicycloazaoctane.

Accordingly, it is a basic object of the present invention to provide novel organic compounds and methods for the preparation thereof.

Another object is to provide novel, physiologically active compounds characterized by chemotherapeutic or medicinal properties, particularly hypotensive activity.

A more specific object is to provide novel compounds, namely, bis-quaternary salts of bicycloazaocane.

is the provision of methods of synthesizing the novel compounds referred to in the foregoing objects.

These and other objects and the manner in which they are accomplished will become apparent to those conversant with the art from the following description of the general class of compounds and certain specific examples of particular members thereof as well as general and specific methods of their synthesis.

The novel chemotherapeutic compounds of the present invention are bis-quaternary salts of 1-methyl-8-dimethyl-3-azabicyclo (3,2,1) octane (camphidine) the base itself being shown in the formula following:

Generally stated, the novel compounds discovered are obtained by forming the N-dialkylaminoalkyl imides of D, DL or L-camphoric anhydride and the reduction of these imides by suitable means to obtain the N-dialkylaminoalkyl camphidine bases which may be converted by appropriate means into their bis-quaternary salts.

Formula 1 shows the general structural formula of compounds obtained by the methods hereafter more particularly described. In this formula, the bicycloazaoctane nucleus is enclosed in parentheses and designated by A. In Formula 1, n is a number from 1 to 6 and R' represents

2

an alkyl group with from 1 to 6 carbon atoms, an alkylene group containing 3 carbon atoms or the structure

may represent a heterocyclic ring namely, morpholine, piperidine, pyrrolidine or piperazine.

10 The simple salts of the bases illustrated by Formula 1 are shown by Formula 2.

and the mono- and bis-quaternary salts of these bases by Formulae 3(a) and 3(b), respectively:

25 In Formulae 2, 3(a) and 3(b), A represents the parent bicycloazo-octane nucleus and X^- represents an anion namely, iodide, chloride, bromide, acetate or sulfate. R, R' and n have the same meaning in all formulae as
 30 described above for Formula 1. In the three latter formulae, i. e., 2, 3(a) and 3(b), the site of both simple and quaternary salt formation on the nucleus A is always the nitrogen at position 3. In the quaternary and bis-
 35 quaternary salts, R'' represents a simple alkyl group having one to three carbon atoms. R'' may be the same as, or different from, R and/or R' in any of the formulae given.

40 Of the compounds described above, the free bases and simple salts possess antihistaminic and bronchodilatory activity. The quaternary salts of these bases, and particularly the bis-quaternary salts thereof, possess a marked hypotensive activity in mammals at a low dosage level and at the same time a favorable therapeutic ratio. In addition, the free bases, Formula 1, possess in varying degree 45 a very discrete moldy or earthy odor which is of value in obtaining this rare type of odor in perfumery or other special preparations in which these particular odoriferous qualities are desired.

50 The following examples of specific compounds and methods will illustrate the manner in the general synthesizing procedure which may be applied to obtain particular members of the class of compounds discovered. It will be understood, however, that the following examples are 55 not nor are they intended to be exhaustive of all compounds embraced by the present invention.

EXAMPLE 1

N-dimethylaminoethyl-*D*-camphidine, simple salts and quaternary salts

60 *The free base.*—The free base has prepared as follows: 40 grams of N-dimethylaminoethyl-D-camphorimide

dissolved in 300 ml. of anhydrous ethyl ether was added dropwise to a rapidly stirred solution of 16 grams (0.44 mole) of lithium aluminum hydride (LAH) dissolved in 600 ml. of anhydrous ethyl ether. The addition was at such a rate as to just maintain a gentle reflux of the ether. After the addition was complete, the mixture was stirred under reflux for an additional 2 hours and allowed to stand over night. The reaction mixture was then decomposed by the dropwise addition of water at such a rate as to just cause reflux of the ether. When the evolution of hydrogen ceased, a slight excess of water was added and the mixture stirred for several hours. The inorganic material was filtered off and the residue washed several times with ether. The ethereal filtrate was dried over anhydrous sodium sulphate, the ether was stripped off and the residue was vacuum distilled to yield 33 grams of N-dimethylaminoethyl-D-camphidine base having a boiling point of 64° C. at 0.4 mm.; $n_D^{25}=1.478$.

The dihydrochloride.—The dihydrochloride, a crystalline hygroscopic salt, was prepared by treating the free base dissolved in ethanol with a saturated ethanolic-HCl solution. It had a melting point 263–4° C. On recrystallization from absolute methanol-anhydrous ether it had a melting point of 265–266° C. and an experimentally determined chloride ion content of 23.41% as compared to 23.85% theoretically calculated.

The monomethiodide.—The monomethiodide was readily obtained in crystalline form by treatment of the free base dissolved in absolute isopropanol with an excess of methyl iodide in a closed system. It had a melting point of 239–240° C. Recrystallization of the salt from anhydrous methanol-anhydrous ether gave the compound with a melting point of 241° C. The iodide ion calculated theoretically was 34.65% and that found to be present in this compound was 34.46%.

The dimethiodide.—The dimethiodide could not be obtained by simple reaction of the free base with methyl iodide in large excess in methanol or ethanol. In fact, only the monomethiodide obtained was prepared by adding the free base to pure methyl iodide. For this reason and on the basis of the following experiments, it is concluded that the monomethiodide described above must be the quaternary salt of the side chain nitrogen and not that of the ring nitrogen. Examination of a molecular model of this molecule showed that the ring nitrogen offered considerable hindrance to the formation of a quaternary salt here. The following experiments illustrate the difficulty of quaternizing the ring nitrogen and the manner in which this was finally accomplished.

Experiment 1.—4 grams of the free base plus 10 ml. of methyl iodide were refluxed for 2 hours in 50 ml. of anhydrous methanol and yielded a white crystalline solid having a melting point of 232–234° C. On analysis, the percentage of iodide ion introduced was found to be 36.76% or only slightly higher than the 34.65% theoretically required for the monomethiodide.

Experiment 2.—Repeating Experiment 1 and refluxing for 12 hours in isopropanol gave a crystalline product with 38.95% iodide ion.

Experiment 3.—Repeating Experiment 1 and refluxing the free base in pure methyl iodide for 3 days gave a discolored crystalline material with 44% iodide ion. The theoretical iodide ion content for the dimethiodide is 49.94%.

Experiment 4.—5 grams of the free base plus 10 ml. of absolute methanol and 10 ml. of methyl iodide heated in a bomb tube at 250° F. for 6 hours on cooling and working up yielded 7 grams of a slightly yellow crystalline material which on recrystallization from absolute methanol-anhydrous ethyl acetate yielded a pure white crystalline compound melting at 244–245° C. with decomposition. Analysis of this compound for iodine content showed a content of 50.05% which is extremely close to the 49.94% theoretical content of the dimethiodide,

indicating therefore that the compound obtained by means of Experiment 4 is in the dimethiodide.

EXAMPLE II

5 *N-dimethylaminopropyl-DL-camphidine, simple salts and quaternary salts*

The free base.—The free base was prepared as described under Example I by reducing 40 grams of the corresponding imide with 16 grams of LAH in anhydrous ether medium. The free base was obtained in 31 grams yield and had a boiling point of 70–72° C. at 0.1 mm.; $n_D^{25}=1.4770$.

The dihydrochloride.—The dihydrochloride was prepared as described under Example I and had a melting point of 290–292° C. Chloride ion calculated theoretically, 22.78%; chloride ion found by analysis, 22.92%.

The monomethiodide.—The monomethiodide, melting point 237–238° C., was prepared by reaction of the free base with an excess of methyl iodide in anhydrous methanol. Its theoretical iodide content is 33.37% and in analysis of the compound so obtained was 33.55%.

The dimethiodide.—The dimethiodide was prepared above under Experiment 4, Example I, the heating at 250° F. being carried on for 8 hours. It had a melting point of 269–271° C. and an iodide content of 48.63% as compared with a theoretical iodide content of 48.60%.

EXAMPLE III

30 *N-diethylaminoethyl-D-camphidine, simple salts and quaternary salts*

The free base.—The free base was prepared as described under Example I, above. Reduction of 40 grams of the imide yielded 29 grams of the base, which has a boiling point of 70–74° C. at 0.1 mm.; $n_D^{25}=1.4780$.

The dihydrochloride.—The dihydrochloride of N-diethylaminoethyl-D-norcamphidine was also prepared as in Example I and was found to have a melting point of 254.5–255.5° C. and a chloride ion content of 21.77% as compared to a theoretical chloride content of 21.66%.

The monomethiodide.—This compound was likewise prepared in the manner described in Example I and has a boiling point of 194–196° C. Analysis showed an iodide content of 31.87% as compared with a theoretical prediction of 32.18%.

The dimethiodide.—This compound was prepared in the manner described under Experiment 4, Example I, above. It has a melting point of 235–236° C. An analysis showed an iodide content of 47.13% as compared to a 47.16% theoretical value.

EXAMPLE IV

55 *N-diethylaminopropyl-D-camphidine, simple salts and quaternary salts*

The free base.—This base was prepared as described under Example I; 40 grams of imide yielded 32 grams of the base which had a boiling point of 83–87° C. at 0.06 mm.; $n_D^{25}=1.4778$.

The dihydrochloride.—This salt was prepared as described under Example I and has a melting point of 212–214° C. The analysis of the salt for chloride ion resulted in a finding of 20.74% as compared with a theoretical content of 20.89%.

The monomethiodide.—The salt was prepared as described under Example I. Its melting point is 196–198° C. and it has an iodide content of 31.13% as compared with a theoretical value of 31.07%.

The dimethiodide.—This compound was prepared as described under Experiment 4, Example I. Its melting point is 217–219° C. and its iodide content is 45.88% compared with 46.12% theoretically calculated.

Other N-dialkylaminoalkyl substitutions have been prepared in similar fashion as shown by the following tables: Table I shows the bases and Table II shows the various salts.

As previously mentioned, the novel compounds disclosed herein are highly efficacious in the treatment of physiological disorders requiring anti-histaminic, bronchodilatory, and hypotensive effects. For relief of hypertension 25 milligrams of the quaternary salts in parenteral solution may be administered once a day or 50-250 milligrams may be given orally in the form of tablets, capsules or the like.

As a respiratory stimulant, the base compounds may be given orally or by injection in 50 milligram doses.

From the foregoing description of a novel class of compounds, particular exemplary members of the class and methods of synthesizing same, it will be understood that, on the basis of the discovery and knowledge disclosed herein, other specific compounds can be made and variations in the methods of synthesis resorted to. Therefore, the specific compounds and methods disclosed herein are to be considered in all respects as illustrative and not restrictive, the scope of the discovery being indicated by the appended claims rather than the foregoing description, and all specific compounds and variations and methods which come within the meaning and range of equivalency of the claims are therefore intended to be embraced therein.

This application is a continuation-in-part of our application Serial No. 388,062, filed October 23, 1953, entitled Bicycloazaocane Derivatives, now abandoned.

We claim:

1. A compound selected from the group consisting of (1) compounds having the formula

where, in said formula, n is a number from 1 to 5 and R is a member of the group consisting of dialkyl groups each alkyl group having 1 to 6 carbon atoms and radicals forming, together with the nitrogen atom to which they are attached, heterocyclic groups consisting of morpholine, piperidine, piperazine and pyrrolidine, and (2) the acid addition salts and mono- and bis-methonium salts of (1).

2. A dimethonium salt of N-dimethylaminoethyl-1-methyl-8,8-dimethyl-3-azabicyclo (3,2,1) octane.

3. The dimethonium chloride of N-dimethylaminoethyl-1-methyl-8,8-dimethyl-3-azabicyclo (3,2,1) octane.

4. A dimethonium salt of N-dimethylaminopropyl-1-methyl-8,8-dimethyl-3-azabicyclo (3,2,1) octane.

5. A dimethonium chloride of N-dimethylaminopropyl-1-methyl-8,8-dimethyl-3-azabicyclo (3,2,1) octane.

6. A dimethonium salt of N-diethylaminoethyl-1-methyl-8,8-dimethyl-3-azabicyclo (3,2,1) octane.

7. The dimethonium chloride of N-diethylaminoethyl-1-methyl-8,8-dimethyl-3-azabicyclo (3,2,1) octane.

8. N-dimethylaminoethyl-1-methyl-8,8-dimethyl-3-azabicyclo (3,2,1) octane.

9. N-dimethylaminopropyl-1-methyl-8,8-dimethyl-3-azabicyclo (3,2,1) octane.
